AUDREE PAULENE KELLER, OF TOLEDO, OHIO.

PROCESS OF FILET-CROCHETING.

1,266,951.

Specification of Letters Patent. Patented May 21, 1918.

Application filed March 26, 1917. Serial No. 157,837.

To all whom it may concern:

Be it known that I, AUDREE PAULENE KELLER, a citizen of the United States, residing at Toledo, in the county of Lucas and

5 State of Ohio, have invented new and useful Improvements in Processes of Filet-Crocheting, of which the following is a specification.

My invention relates to a process of filet crocheting, and has for its object to provide 10 a method of filet crocheting, whereby crochet work of the kind is produced in a plurality of colors, wherein one thread is used for forming the open mesh back ground and another thread or threads are individually 15 used for forming the filled in meshes composing the figure design of the work, and wherein the several threads are unbroken and when used severally constitute the body of the meshes, and whereby the work is of 20 the same appearance and construction on both sides with continuous unbroken threads and stitches.

I accomplish these objects by the process and combination of threads, as hereinafter 25 described and illustrated in the drawings, in which—

Figure 1 illustrates the position and method of holding the design thread while 30 versa, and

being covered in by the base thread or vice Fig. 2 illustrates the method of dropping a design thread.

In the drawings 1 designates the work, and 2 and 3 respectively designate the base 35 thread and the colored design thread of which the open meshes of the base of the work and the closed meshes of the design of the work are respectively formed.

The principle involved in my process of 40 filet crocheting in its simplest form is to form by the ordinary and well known open stitch of the thread desired for the base of the work, the open square meshes in rows across one end of the work until a row is 45 reached in which is included any part, however small, that is the nearest portion to that end of the work, of the design that is to be embodied in the work in filet meshes. When near this point in the formation of the base 50 row of open meshes an end portion of a thread of the color desired for the design that is to be worked into the base by closed meshes is drawn as a loop by the needle, through a mesh opposite a cross connection with the 55 next preceding row. A second loop of the colored thread (which will hereinafter be

designated as the design thread 3) is drawn through the same mesh in an opposite direction to the first loop, and the two loops are tied together in a flat knot.

60

Holding the loops together with the design thread 3 along the edge of the work in the position of the thread 3 as shown in Fig. 1, the base thread 2 is used to form open meshes alternately over and under the design

65

thread and its loops, whereby the meshes are made to entirely cover the design thread until the point is reached in the row being formed where the design begins. The base thread and the design thread are then re- 70 versed in their positions shown in Fig. 1, and after making a couple of stitches with the design thread to lock the design thread to the last open base mesh, filet meshes are formed with thread 3 alternately over and

75

under the base thread 2 held taut forward along the edge of the last complete row of the work, whereby the base thread is entirely covered and concealed until an interval in the design occurs. The threads are 80 then again reversed in position, as shown in Fig. 1 and the base thread is used to form open meshes covering the design thread across said interval. When the open meshes formed of the base thread for the interval

85

are completed the base thread is secured by tying stitches and again carried forward along the edge of the work and held in position as shown in Fig. 1 while the design

90

thread is used to form filet meshes under and over the base thread as before described. In like manner the intervals of design and base are completed until the outer limit of the design in the row is reached. The positions of the threads are again reversed and

95

the design thread is covered in by the base thread up to a point opposite the beginning of the design in the next succeeding row. The design thread is then drawn back between the thumb and forefinger of the right hand, as shown in Fig. 2, and after the tying stitches of the base thread are formed the design thread is dropped and the row is completed with the base thread alone.

100

Upon completion of the row the work is 105 reversed in position and the base thread is used for the formation of the open meshes of a new row until a point is reached opposite where the design thread was dropped in the formation of the next preceding row.

110

After forming tying stitches with the design thread it is used in alternation with the

base thread for forming the design and base portion of the work of the row in like manner as already described, and in like manner each row is formed until the design is completed, when the design thread is finally dropped out at the limit of the design work and the remaining rows are completed with the design thread alone.

It will thus be seen that the base thread is continuous from side to side of the work in each row and the design thread is taken up at the point in each new row at which it is left in the last completed row, and used continuously or intermittently in the formation of closed meshes, according to the requirements of the design. At all places of intermission the design thread is tied with stitches and then drawn forward and covered by under and over stitches of the base thread formed into open meshes, and is finally dropped out of the row, when the design is no longer included as part of it, the row being completed with open meshes formed of the base thread.

While the design thread is for the most part worked into closed meshes, open meshes are formed of the design thread wherever they form a part of the design. Wherever they occur, the base thread drawn taut forward is covered by the stitches of the design thread looped over and under the base thread in forming the open meshes, in like manner as the open meshes of the base thread are formed around the design thread as hereinbefore described.

It is manifest that without departing from the principle of the simple form of my process hereinbefore described the design may be formed of a plurality of different colored threads which may be introduced or taken up and used as they occur in the design and carried forward either singly or in groups with other design threads, or dropped, as the design requires, wherever they do not again occur in the row being formed, and I therefore in carrying out my process do not limit myself to any number of different colored design threads, except only as the design is so limited.

Crochet work produced by my process, as herein described, has the same appearance on both sides, which are alike free from protruding ends or knots or threads.

While the design thread or threads are preferably severally first introduced in the work at or near the points where they respectively first occur in the design, it is manifest that they may respectively be introduced at the beginning of any row in which they respectively first occur, and from such point, being drawn forward along the last row of the work completed, be covered in by the base thread as the open meshes of the new row are formed, or by another design thread used in the preceding

row and dropped out in the formation and development of the design until the point is reached where the use of the newly introduced design thread is required, and from such point be then used for the formation of the meshes, instead of the base or design thread previously used in the formation of the meshes of the row, which are in turn drawn forward with the base thread and covered, or dropped, according to the requirements of the design, as hereinbefore described. I therefore do not limit myself to the first introduction of any design thread to the point where it first occurs in the design.

What I claim to be new is—

1. The process of filet crocheting, comprising the use of a base thread of one tint for forming the ground work, and the use of a design thread of a different color for the design work, and wherein the base thread is continuous throughout the whole work, and the design thread is continuous throughout the area included within the outer limits of the design and covers the base thread stretched forward along the work, where the design appears, and is stretched forward and covered in by the base thread in the ground work where it appears within the area included within the outer limits of the design work, the design thread and the base thread respectively, being severally secured by tying stitches before being stretched forward and covered in by meshes formed by the other of them, the base and design threads, within the outer limits of the design work, being manipulated simultaneous.

2. The process of filet crocheting, comprising the use of a base thread of one tint for forming the ground work, and the use of a design thread of a different color for the design work, and wherein the base thread is continuous throughout the whole work, and the design thread is continuous throughout the area included within the outer limits of the design and covers the base thread stretched forward along the work, where the design appears, and is stretched forward and covered in by the base thread in the ground work, where it appears within the area included within the outer limits of the design work, the design thread and the base thread respectively, being severally secured by tying stitches before being stretched forward and covered in by meshes formed by the other of them, and the design thread being taken up and used for forming filet meshes at the beginning of the design in the formation of a row being formed, and dropped out thereof at the point where the design first appears in the next succeeding row, the base and design threads, within the outer limits of the design work, being manipulated simultaneously.

3. The process of filet crocheting, comprising

- ing the forming of a background of open meshes with a single continuous thread of a desired tint, and forming a design therein with another thread of a different color, by 5 using the background thread for forming the open meshes of the background to the point of the beginning of the design, then introducing and tying into the meshes of the background the design thread, and there- 10 after forming each row of the work by holding the background thread stretched forward along the next preceding row and forming filet meshes around and covering the background thread in the intervals 15 where the design occurs in the row, and forming the open meshes of the background with the background thread in the intervals where the background occurs therein, with the design thread stretched forward along 20 the preceding row, and covering it with the open meshes of the background thread, the design thread being secured by tying stitches at a point opposite the outer limit of the design of the next succeeding row, and dropped, 25 and the remaining part of the row and the end portion of the next succeeding row to the point of dropping the design thread being formed with the background thread, and in like manner as described forming the de- 30 sign portions of each row with the design thread by covering in the background thread, and the background portions of each row within the end limits of the design with the background thread covering the design 35 thread, substantially as set forth, the base and design threads, within the outer limits of the design work, being manipulated simultaneously.
4. As a new article of manufacture, a 40 crocheted fabric body having a background portion formed of a thread of one color and a design portion formed of a thread of an-
- other color, and wherein the background thread is continuous throughout the entire area of the crocheted body, and is covered in by the design thread and invisible in the area where the design appears, and the design thread is continuous throughout the portion of the area of the crocheted body that is included within the outer limits of the design, and is covered in by the background thread and invisible wherever any portions of the background of the body appear within the outer limits of the design. 45
5. As a new article of manufacture, a 50 crocheted fabric body having a background portion formed of a thread of one color and a design portion formed of a plurality of threads, each of a different color from the others, and from the background thread, and wherein the background thread is continuous throughout the entire area of the crocheted body and is covered in by a design thread and invisible in the area where the design appears, and the design threads are sev- 55 erally and individually continuous throughout the portion of the area of the crocheted body that is included within the outer limits of the design, after their first and last appearance therein, and are covered in by the 60 background thread and invisible wherever any portion of the background portion of the body appears within the outer limits of the design, and severally within the limits of their first and last appearance in the de- 65 sign. 70
- 75

In testimony whereof I have hereunto set my hand at Toledo, Ohio, this 21st day of March, 1917.

AUDREE PAULENE KELLER.
